CLAIM

The ornamental design for an oven in the shape of a fireplace, as shown and described.

DESCRIPTION

FIG. 1 is a front view of an oven in the shape of a fireplace showing my new design;
FIG. 2 is a top view thereof;
FIG. 3 is a right side view thereof;
FIG. 4 is a left side view thereof;
FIG. 5 is a perspective view thereof seen from the top and the front; and,
FIG. 6 is a bottom view thereof.
The undisclosed rear is flat and unornamented.
